FEEDING MECHANISM FOR SEWING MACHINES

Andrew B. Clayton, Union, N. J., assignor to The Singer Manufacturing Company, Elizabeth, N. J., a corporation of New Jersey

Application November 24, 1937, Serial No. 176,190

9 Claims. (Cl. 112—214)

This invention relates to feeding mechanism for sewing machines, more particularly of the type having a main four-motion feed-dog the action of which is assisted by an auxiliary feed-member which may be a step-by-step driven puller feed-roll arranged in rear of the feed-dog. Machines of this type are commonly used for heavy sewing operations, such as sewing strips of fringe to the end edges of rugs. In doing this and other similar work it is often desirable that the initial and finishing stitches of the seam be shorter than the intermediate stitches, to more securely fasten the ends of the fringe strips.

The present invention therefore has for an object to provide means operable at will, and while the machine is sewing, to simultaneously and equally adjust both the main feed-mechanism and the auxiliary puller feed-mechanism of the machine, so that the stitch-length determining means of the machine are under the constant control of the operator, without stopping the machine or interfering with the normal and proper operation of the auxiliary feed-mechanism as an aid to the main or four-motion feed-mechanism of the machine.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings Fig. 1 is a front end elevation of a sewing machine embodying the invention. Fig. 2 is a plan view of the machine bed and the mechanism mounted thereon. Fig. 3 is a rear elevation of the parts shown in Figs. 1 and 2. Fig. 4 is a section on the line 4—4, Fig. 2, looking toward the right or in the direction of the arrows. Fig. 5 is a section on the same line 4—4 but looking in the opposite direction. Fig. 6 is a section on the line 6—6, Fig. 3. Fig. 7 is a section on the line 7—7, Fig. 3. Fig. 8 is a disassembled perspective view of the main feed-adjusting lever and parts associated therewith and Fig. 9 is a disassembled perspective view of the puller feed-adjusting lever and parts associated therewith.

The invention is disclosed as embodied in a sewing machine having a frame including the bed 1 and standard 2 of the usual gooseneck terminating in the head 3 which carries the usual reciprocating needle-bar 4 and spring-pressed presser-

bar 5. The needle-bar 4 carries the two needles 6 which cooperate with the usual thread-carrying loopers 7 actuated by suitable mechanism driven by the main shaft 8.

The main feeding mechanism of the machine comprises the four-motion feed-dog 9 which is carried by the feed-bar 10 fulcrumed at 11 on the upstanding feed-rocker 12. The feed-rocker 12 is pivoted on the lower fulcrum-pin 13 and is formed at one end with a curved, upwardly extending arm 12', Figs. 2 and 3, having cut therein the arcuate slot 14 for the slide-block 15 carried by the eccentric portion 16 of the pin 17 which is clamped between its ends by the split end 18 of the pitman 19 embracing the conventional adjustable main feed-eccentric 20 on the main shaft 8. The pin 17 may be rotatably adjusted in the pitman 19 to centralize the feed-dog 9 longitudinally of the usual feed-dog slots 9a in the throat-plate 9b.

Obviously, as the slide-block 15 and pin 17 are shifted upwardly along the arcuate slot 14 in the feed-rocker extension 12', the feeding stroke of the feed-dog 9 is shortened. In the present machine, treadle-controlled means are provided for making this adjustment at will without stopping the machine.

To this end there is provided a lever 21 having a double-forked end 22 which straddles the split end 18 of the pitman 19 and embraces the pin 17. The lever 21 has a hub 21' which is journaled to turn freely upon the puller-feed shaft 23 supported in bearings 24 on the auxiliary bed-casting 25 screwed to the rear side of the main bed casting 1. Clamped upon the hub 21' of the lever 21 is the lever-arm 26 which extends rearwardly of the machine and is connected at its free end by a link 27 to a treadle-controlled lever 28 fulcrumed at 29 on the machine bed. The treadle-controlled lever system 21, 26, 27, 28 is biased in a direction to carry the pin 17 toward the fulcrum 13 of the feed-rocker 12 (long-stitch position) by a coil-spring 30 which is connected at its upper end to the lever 21 and at its lower end to an anchorage 31 on the auxiliary bed-casting 25. The chain 32 depending from the lever 28 is to be connected to the usual foot pedal. By the means described, the operator may instantly adjust the feed-stroke of the main feed-dog 9 to and maintain it at any desired value, within the limits provided, while the machine is in operation.

Mounted on the puller-feed shaft 23 is a puller-feed roll 33 which is located, as usual, behind the main feed-dog 9 and in line therewith, so as to engage and pull the stitched seam passing

rearwardly from under the usual presser-foot 34 carried by the presser-bar 5.

The feed-roll 33 cooperates with the free presser-roll 35 which is fixed to the shaft 36 journaled 5 in the yoke 37 fixed to the spring-pressed presser-bar 38 mounted in the bracket 39 screwed to the frame-head 3. The presser-bars 5 and 38 may be manually lifted, for introduction or removal 10 of work, by the usual hand lifter levers 40, 41, respectively; the latter having a latch 42 which engages a corner shoulder 43 on a frame-plate 44, to hold the presser-roll 35 in elevated position.

The puller feed-shaft 23 is given a step-by-step 15 rotary motion by means of the conventional adjustable feed-eccentric 45 on the main shaft 8. This eccentric is connected by a pitman 46 to a slotted crank-arm 47 depending from the live 20 oscillatory clutch-roll spider 48, Fig. 6, loose on the shaft 23 and having a clutch-roll-carrying portion entering a clutch-cavity 49, Fig. 3, in one end of the cylindrical member 50 fast to the shaft 23. A stationary anchor clutch-roll spider 51 fast to the bearing bushing 52 has an 25 anchor clutch-roll-carrying portion entering a cavity 53 in the other end of the cylindrical member 50. The stationary spider 51 has depending from it a rigid arm 54 the forked lower end of which embraces an anchor block 55 fixed to the 30 auxiliary bed 25. The mechanism of the live and stationary clutch-roll spiders 48, 51, with the intermediate cylindrical member having clutch-roll cavities in its opposite ends, is the conventional puller-feed operating clutch disclosed, for 35 example, in U. S. Patent No. 1,980,603, dated Nov. 13, 1934. Heretofore, however, the adjustable eccentric 45 on the main shaft was the sole means of varying the length of feed of the puller feed-roll. To make this adjustment it was necessary to stop the machine.

According to the present improvement the connection between the pitman 46 and puller-clutch 40 crank-arm 47 is a variable one and is controlled by the same treadle mechanism which controls the stroke of the main feed-dog. To this end, the pitman 46 has clamped in its rearward split 45 end a cross-pin 56 which is supported and guided by the slots 51 in the lever 28 which has formed integral therewith a cheek-piece 28' spaced laterally from the main body of such lever and containing one of the slots 57. The cross-pin 56 carries a slide-block 58 which works in the 50 arcuate slot 59 in the puller-feed-operating crank-arm 47.

Thus the puller feed-stroke will be greater 55 when the pin 56 occupies a position nearer the axis of the shaft 23. A pull on the treadle chain 32 simultaneously actuates the levers 28 and 21 and carries the cross-pins 56 and 17 to the respective positions shown in dotted lines in Figs. 4 and 5. This shortens the feed-stroke or movement of both the main feed-dog 8 and puller feed-roll 33. The two feed-eccentrics 20 and 45 are independently adjustable enabling the feeding 60 movements of the feed-dog and puller feed-roll to be substantially equalized for the long stitch position of the parts (full lines Figs. 4 and 5). The parts of the treadle-controlled feed-adjusting mechanism are so proportioned that the feed-strokes of the main feed-dog and puller feed-roll are maintained substantially equal to each other in any position of the feed-adjusting lever 28.

Thus both feeds may be simultaneously and 70 equally adjusted by means under the control of

the operator, without stopping the machine. Short stitches may be readily applied at will to the beginning and ending or other desired portions of a seam, and the original set stitch-length restored at a moment's notice.

As shown in Fig. 1, the main shaft 8 carries the usual feed-lift eccentric 60 which is embraced by the strapped end 61 of the feed-lift pin 62 slidably received in a bore in the feed-bar 10.

The adjusting lever system 21, 26, 27, 28 constitutes means interconnecting the pitmen 19 and 46 to adjust them simultaneously along the slots 14, 59 in the respective crank-arms 12', 47 to which they are connected.

The two eccentrics 20 and 45 are so set or 15 timed upon the main shaft 8 as to impart simultaneous feed-impulses to the feed-dog 8 and feed-roll 33.

The invention is not to be understood as limited to the details of construction and relative 20 arrangements of parts of the particular embodiment of the invention chosen for the purposes of the present disclosure. The foregoing specification is to be read as illustrative of and not in limitation of the invention which may obviously 25 be embodied in many specifically different forms within the spirit and scope of the invention.

Having thus set forth the nature of the invention, what I claim herein is:

1. A sewing machine having stitch-forming 30 mechanism, a main shaft, a main feeding mechanism including a four-motion feed-dog, auxiliary puller feed-mechanism including a puller feed-roll acting on the work in rear of said feed-dog and arranged to feed the work at substantially 35 the same speed as said feed-dog, and manually controlled means to simultaneously adjust the work-feeding speeds of said feed-dog and puller-feed roll, without stopping the stitch-forming mechanism.

2. A sewing machine having stitch-forming 40 mechanism, a main shaft, an adjustable main feed eccentric thereon, main feeding mechanism receiving its feed-stroke movements from said eccentric, auxiliary feed-mechanism, a second 45 and independently adjustable eccentric on said main-shaft connected to actuate said auxiliary feed-mechanism in step with the main feeding mechanism, and manually controlled means exclusive of and additional to said eccentrics and 50 operable without stopping the machine to simultaneously vary the work-feeding movements of said feeding mechanisms.

3. Feeding mechanism for sewing machines comprising a feed-dog, a feed-bar carrying said feed-dog, a feed-rocker to which said feed-bar is pivotally connected, a slotted crank-arm connected to said feed-rocker, an eccentric-driven pitman connected to said slotted crank-arm, a puller feed-roll, a feed-roll-actuating clutch having a slotted crank-arm to actuate it, an eccentric driven pitman connected to the slotted crank-arm of said puller feed-clutch, and adjusting means interconnecting said pitmen to adjust them simultaneously along the slots of 65 the respective crank-arms to which they are connected.

4. In feeding mechanism for sewing machines, the combination with two work-engaging feed-elements, of means to impart simultaneous step-by-step work-feeding movements to said elements including means to adjust the amplitude of the work-feeding movement of each of said elements relative to the other, and means to simultaneously and equally vary the amplitude 70

of the work-feeding movements of both of said elements.

5. The combination with a main four-motion feed-mechanism, of a step-by-step driven puller feed-mechanism, adjusting means to substantially equalize the work-feeding movements of said mechanisms, and other means to simultaneously and equally alter the work-feeding movements of said mechanisms, while said mechanisms are in motion.

6. The combination with main and puller-feed mechanisms and a main shaft connected to drive said mechanisms, of means to substantially equalize the work-feeding speeds of said mechanisms, and means to simultaneously alter the work-feeding speeds of said mechanisms relative to the speed of said main shaft while maintaining the substantial equality of said work-feeding speeds.

15 7. The combination with a four-motion feed-mechanism, of a puller feed-mechanism substantially equalized and synchronized therewith, a main shaft connected to drive said feed-mechanisms, and means to simultaneously and equally

vary the work-feeding speeds of said feed-mechanisms relative to the speed of said main shaft, while the main shaft is in motion.

8. In feeding mechanism for sewing machines, a main shaft, a pair of independently adjustable feed-eccentrics thereon, a four-motion feed-dog receiving its feed-and-return movements from one of said feed-eccentrics, a puller feed-roll receiving its feed-movements from the other of said eccentrics, and means under the control of 10 the operator to simultaneously and instantly change the amplitudes of the feed movements of said feed-dog and puller feed-roll, while the main shaft continues to run at its full normal operative speed.

15 9. In a sewing machine, a main shaft, four-motion and puller feed-mechanisms actuated thereby, independent adjusting means to vary the work-feeding speeds of each of said mechanisms, and other means to simultaneously vary 20 the work-feeding speeds of said mechanisms while the speed of the main shaft remains constant.

ANDREW B. CLAYTON.
